VACUUM TUBE

Harold A. Snow, Mountain Lakes, N. J., assignor
to Radio Corporation of America, a corpora-
tion of Delaware

Original application December 13, 1930, Serial
No. 437,225. Divided and this application July
2, 1931, Serial No. 548,299. Renewed June 26,
1934

11 Claims. (Cl. 250—27.5)

The present application relates to space dis-
charge tubes of the type including a cathode, two
grids and an anode, and is a division of my ap-
plication, Serial No. 437,225, filed December 13,
5 1930 which in general relates to variable mu
tubes.

The method of operation and the advantages
of vacuum tubes of the variable mu type dis-
closed by this application are discussed more fully
10 in the aforesaid application and in the Pro-
ceedings of the Institute of Radio Engineers for
December, 1930, wherein in an article by Stuart
Ballantine and Harold A. Snow, entitled "Reduction
15 of distortion and cross-talk in radio re-
ceivers by means of variable-mu tetrodes" there
is demonstrated the intimate relationship be-
tween the problems of distortion and cross-talk
in radio frequency amplifiers, and their elimi-
nation by means of variable mu tubes.

20 It is, therefore, one of the main objects of the
present invention to provide a space discharge
tube having such operating characteristics that
no distortion is introduced when, for increasing
25 signal strengths, the operating potentials
are so adjusted that the amplification rate is re-
duced to a small fraction of the maximum am-
plification.

30 A further object of the invention is to provide
an electron discharge tube having such charac-
teristics, that when the potentials are adjusted
to give a relatively low amplification of strong
35 signals, the change in transconductance for a
given change in the gain control voltage is much
lower than is the case with the known types of
tubes.

Another, and important object of the inven-
40 tion is to provide a high frequency amplifier tube
of the type which has two grids and which is
capable of adjustment to give an undistorted out-
put of approximately constant magnitude over a
45 wide range of applied carrier voltages.

A more specific object of the invention is to
provide an electronic amplifier of the screen grid
45 type in which different portions of the electron
stream are influenced at different rates by the
voltages applied to the control grid.

The novel features which I believe to be char-
acteristic of my invention are set forth in par-
ticularity in the appended claims, the invention
50 itself, however, as to both its organization and
method of operation will best be understood by
reference to the following description taken in
connection with the drawing in which I have in-
dicated diagrammatically several arrangements

whereby my invention may be carried into effect.

In the drawing,

Fig. 1 is a perspective view, partly in section, of
a screen grid tube embodying the invention,

Fig. 2 is a diagrammatic view illustrating an-
other embodiment of the invention, and

Fig. 3 is a curve sheet showing the variations of
plate current with grid bias for a tube such as
shown in Fig. 1.

Referring to the accompanying drawing where-
in like reference characters in the different fig-
ures designate the same elements, the tube shown
in Fig. 1 is a form of tube known commercially
as a screen grid tube, with an equipotential cath-
ode having a separate heater for the cathode. 15
As is well known, this particular type of tube
comprises an evacuated envelope enclosing a
cathode C, heated by a resistance heater (not
shown) within the cathode, an inner grid CG,
a second or screen grid SG, a plate, or anode 20
P, and an outer screen S which is electrically
connected to the second grid. Except for the
novel construction of the control grid CG and
of the second or screen grid, the several ele-
ments of the tube, and their relative physical 25
arrangement, may be substantially the same as
that employed in the present commercial tubes.

In tubes of this general type, the control grid
comprises a helical winding supported by one
or more wires 1. In the tube shown in Fig-
30 ure 1, the helical winding is not continuous, as
in the known constructions, but comprises two
sections 2, 2 that are separated by a distance of
the order of twice the pitch of the winding. The
windings of each section are of the same pitch, 35
which may be the same as that now employed
in tubes of this type. This particular physical
embodiment of the invention therefore physical-
ly differs from the known construction, of the
same general physical design, by the absence of 40
two complete circumferential turns of the con-
trol grid winding.

This particular construction results in a tube
in which the control exercised upon the electron
stream is not uniform over the entire extent 45
thereof.

The operation of the tube shown in Fig. 1 may
be explained as follows:

The control grid has been shown to be divided
into two sections which are mounted with a gap 50
between them. At low negative biases the entire
cathode is operative, and the tube has about the
same characteristics it would have if the gap
were in place. As the grid bias increases nega-
tively the electron current through the upper and 55

lower parts of the control grid are cut off leaving a low mu control through the gap. At these bias voltages the tube acts as if the upper and lower sections of the control grid were formed of solid metal, and controlled the current through the gap in the ordinary manner.

It will be apparent that various combinations of the described constructions may be included in a single tube. As shown in Fig. 2, the screen grid 10 SG may comprise two cylindrical sections of different diameters, and the control grid CG may be one wherein the winding pitch is not uniform throughout the entire length of the grid, the grid shown in Fig. 2 being of progressively varying 15 pitch from one end to the other.

To prevent the flow of an excessive plate current the larger diameter section of the screen grid is located opposite the portion of the grid of greater pitch.

20 The mode of operation of the modification disclosed in Fig. 2 can be explained in the same manner as has been explained in connection with the embodiment shown in Fig. 1. Essentially, and basically considered, all of the tube structures disclosed herein provide a radio frequency amplifier tube having a mu-factor which decreases continuously with increasing negative grid bias.

30 It is well known that the amplification of a vacuum tube may be regulated by adjusting the bias voltage upon the control grid, the amplification decreasing as the bias voltage becomes more negative. Curves showing the relation between plate current and grid bias, i. e., transfer 35 characteristics, afford an indication of the amplification at different bias voltages, since the slope of the curve at any point is a measure of the amplification when the tube is biased for operation at that point.

40 In Fig. 3, the solid line curve A is the transfer characteristic for a tube such as shown in Fig. 1, and the dotted line curve B is a similar curve for a commercial screen grid tube of the same general type but having a continuous control grid winding of uniform pitch. An examination of 45 curve A shows that, with tubes embodying the invention, a control of amplification extends over a range of control grid bias of from zero to more than -30 volts. With the known tubes, the curvature of the transfer characteristic approaches zero at a control grid bias of about -15 volts.

50 In other words, an increase of the grid bias above approximately 15 volts negative will not be accompanied by a decrease in amplification when the known type of tube construction is employed, but with tubes embodying the invention, the amplification may be varied with changes of control grid bias throughout a range of from zero to upward of -30 volts. The tubes will still pass signals, by leakage transmission when the control grid biases exceed these respective values, but control of amplification is no longer possible in regions where the transconductance curves become substantially horizontal.

55 Modulation distortion may occur when, for a given signal strength, the amplification is so adjusted as to bring the output down to a desired, or standard, level. Since such distortion is due to the curvature of the transfer characteristic it will be apparent that a tube having a curve of lower curvature can transmit, without distortion, higher voltage signals than a tube having a characteristic which exhibits a region of higher curvature. An examination of the

curves of Fig. 3 will show that the maximum curvature of curve A is substantially lower than that of curve B.

It is to be understood that the physical construction of the control grid, or the geometric and structural relationships of the tube elements are subject to wide variation so long as the control grid exercises different rates of control at different portions of the electron stream. Considered broadly, the invention provides in a single 10 tube, the electrical equivalent of two, or more, amplifier tubes operating in parallel, one tube having a relatively high ratio of plate voltage to control grid voltage (high mu), and one or more, of the remaining tubes having lower ratios of 15 plate voltage to control grid voltage (low mu). A single tube exhibiting these characteristics will usually be more economical and convenient than the parallel tube arrangement.

20 By transconductance is meant the ratio of the change in the current in the circuit of an electrode to the change in the voltage on another electrode, under the condition that all other voltages remain unchanged. By mu-factor is meant the ratio of the change in one electrode voltage 25 to a change in the other electrode voltage, under the condition that a specified current remains unchanged.

30 While I have indicated and described a preferred way of carrying my invention into effect, it will be apparent to one skilled in the art that my invention is by no means limited to the particular organization shown and described, but that many modifications may be made without 35 departing from the scope of my invention as set forth in the appended claims.

What I claim is:

1. A vacuum tube comprising a cathode, a screen grid and a plate, control means of progressively varying pitch positioned between said cathode and plate to exercise different rates of control at different portions of the electron stream between said cathode and plate, the said screen grid including at least two cylindrical sections of different diameters to exercise a decreased accelerating action upon the electron stream at those portions of the stream at which the control action of said control grid is decreased.

2. An electron discharge tube comprising a cylindrical unipotential cathode, a control grid surrounding said cathode and exerting different rates of control on different portions of the electron stream from said cathode, at least one grid-like auxiliary cold electrode surrounding said control grid and comprising two adjoining sections of uniform pitch but of different diameters and both surrounding said control grid, and a plate electrode surrounding said auxiliary electrode.

3. An electron discharge tube comprising a cathode, a helical control grid surrounding said cathode and having adjacent portions of different pitches, a helical screen grid surrounding said control grid and comprising two sections each of the same pitch but of different diameters mounted end to end with the larger diameter section in registry with the more open portion of said control grid, and a plate electrode surrounding 65 said screen grid.

4. An electron discharge tube comprising a cathode, a control grid having a grid wire wound into a helix with a pitch progressively increasing from one end of said grid to the other, a helical 70

screen grid of at least two sections each of uniform pitch, said sections being of different diameters and mounted with the sections of smallest diameter surrounding the more closely wound end of said grid, and a cylindrical plate electrode, said grids, and said plate being mounted coaxially with and surrounding said cathode.

5. An electron discharge device comprising a cylindrical unipotential cathode, a control grid 10 surrounding said cathode and comprising a helix of progressively increasing pitch, and another grid-like electrode surrounding said control grid and of different diameters at different points 15 along its length, the portion of greatest diameter being in registry with the control grid portion of greatest pitch.

6. An electron discharge device comprising a cylindrical unipotential cathode, a control grid surrounding said cathode and comprising a helix 20 of progressively increasing pitch, and another grid-like electrode surrounding said control grid and having at least two parts of different diameters, the part of lesser diameter being in registry with the control grid portion of lesser pitch and 25 the part of greater diameter in registry with the control grid portion of greater pitch.

7. An electron discharge device comprising a cathode, an anode, a control grid having portions 30 of different pitch, and a screen grid having two sections of uniform pitch and different diameters, with the section of greater diameter in registry

with the portion of said control grid of greater pitch.

8. An electron discharge device comprising a cathode, an anode, a perforated control grid more open near one end than the other to exert at the 5 more open end less control on the electron stream from the cathode to said anode, and a screen grid surrounding said control grid and having sections of different diameters mounted end to end, each of said sections being of uniform diameter 10 throughout.

9. An electron discharge device comprising a cathode, an anode, a control grid of progressively increasing pitch, and a screen grid coextensive 15 with said control grid and larger at one end than at the other.

10. An electron discharge tube comprising a cathode, a helical control grid surrounding said cathode and having portions of different pitch at different points along its length, and another 20 grid-like electrode surrounding said control grid and having two cylindrical portions of different diameters in registry with the portions of said control grid of different pitch.

11. An electron discharge tube comprising a 25 cathode, a control grid having at different points along its length different rates of control of the electron stream from said cathode, and a cooperating electrode having cylindrical sections of different diameters surrounding said control grid at 30 different points along its length.

HAROLD A. SNOW.
